UNITED STATES PATENT OFFICE.

ADOLPH W. SCHRAMM, OF RIVERTON, NEW JERSEY, ASSIGNOR TO ELECTRO DENTAL MANUFACTURING COMPANY, OF PHILADELPHIA, PENNSYLVANIA, A CORPORATION OF PENNSYLVANIA.

ELECTRIC SWITCH.

Application filed July 13, 1921. Serial No. 484,355.

To all whom it may concern:

Be it known that I, ADOLPH W. SCHRAMM, a citizen of the United States, residing in Riverton, Burlington County, New Jersey, have invented the Electric Switch, of which the following is a specification.

This invention relates to that class of switches including a number of fixed contacts positioned to cooperate with a single movable contact for permitting current flow in any of a number of circuits or in any of the branches of the same circuit, and one object of said invention is to provide a switch whose construction shall be such as to prevent the possibility of the movable contact simultaneously engaging any two adjacent fixed contacts.

The invention further contemplates a multi-point switch of the above noted type whose construction shall be such as to prevent the short circuiting between any two of the fixed contacts by the movable contact, even though the distance between said fixed contacts is less than the width of the part or parts of the movable contact cooperating therewith:—the construction being such as to insure the high speed disengagement of the movable contact from each of the fixed contacts and its immediate engagement with another and adjacent fixed contact so that any flash or arc produced is reduced to a minimum.

The invention also contemplates a quick break multi-point switch having the above named characteristics, which will make impossible the short circuiting of the adjacent fixed contacts by the movable contact regardless of the direction of the movement of the latter, and whose construction shall be relatively durable, simple, compact and inexpensive as well as not likely to get out of order nor require any but a minimum of attention and repair.

In electric switches associated with rheostats and similar apparatus, it has hitherto been customary to so arrange and construct the parts that the movable contact member will either short circuit two adjacent fixed contacts or will be of such dimensions as to be incapable of simultaneously engaging two such contacts and will consequently break the circuit in which it is included. Another object of my invention is, therefore, to provide an electric switch of such

construction that the movable contact member cannot at any time short-circuit or simultaneously engage two adjacent fixed contacts, nor be moved into a position in which it will break the circuit in which it is included or in which it does not engage one of the fixed contacts.

These objects and other advantageous ends I attain as hereinafter set forth, reference being had to the accompanying drawings, in which,

Fig. 1 is a plan of a switch constructed in accordance with my invention;

Fig. 2 is a vertical section on the line 2—2, Fig. 1;

Figs. 3 to 12 inclusive are vertical sections on the line 3—3, Fig. 1, showing diagrammatically the movable contact member in certain of its different operative positions relatively to the fixed contacts;

Fig. 13 is a perspective view of one of the fixed contacts;

Figs. 14 and 15 are perspective views of the free end of the movable contact;

Fig. 16 is an elevation of one end of one of the fixed contacts;

Fig. 17 is a perspective view of the free end of a special form of movable contact;

Fig. 18 is a plan, to some extent diagrammatic, showing a modified form of my invention; and

Fig. 19 is an end elevation of the movable contact.

In the above drawings, 1 represents a suitable base or supporting structure of insulating material including, in the case illustrated, a circularly curved strip 2 projecting from one face and serving to support a series of fixed metallic contacts 3 above the level of the main portion of said base. These are held to said strip in the present instance by screws 4 which may serve as binding posts, although obviously electrical conductors may be connected to these contacts in any way desired without departing from my invention.

In accordance with my invention each of the fixed contacts 3 is made of relatively stiff metal strip or plate such as brass, and are arranged on their supporting structure 2 concentrically with a spindle 5 which has fixed to it a radially projecting metallic strip or plate 6 constituting the movable contact of the switch. Each of the fixed

contacts projects inwardly from the supporting structure 2 toward said spindle 5 and its inner portion or free end 7 is twisted, bent or otherwise so formed as to lie at an acute angle to the plane of motion of the lever. Each of said contacts is electrically insulated from all of the others and the side edges of the portions 7 are oppositely bevelled.

10 For example, with the above described arrangement the left edges or sides of the fixed contacts lie in a plane above and parallel with a plane including their right sides, while the top and bottom faces of said contacts are approximately plane and parallel. 15 The movable contact 6 in the present instance is connected in any suitable manner to the spindle 6 which likewise has fixed to it an operating handle or head 8 and is rotatably mounted in the supporting structure 1 where it is held by a pair of retaining nuts 9 and 10. The nut 10 serves to 20 electrically connect a suitable conductor to the spindle and therefore to said movable contact, although obviously the latter may be connected into a circuit by any other suitable means without departing from my invention.

25 Said contact 6 is peculiar in being formed of a more or less springy metallic plate or strip whose outer or free end is split or forked to form two contact engaging fingers 12 and 13 each of which is twisted or bent so that it may engage and lie parallel with 30 either the top or the bottom faces of the projecting portions 7 of the fixed contacts. These fingers are vertically separated by a 35 space whose width is somewhat less than the thickness of the projecting portions 7 of the fixed contacts which are bent to such an extent that the perpendicular distance between any two adjacent contacts is greater than the thickness of the fingers 12 and 13. Two stops 14 and 15 are provided on the 40 supporting structure 1 to limit the movement to said movable contact as the spindle 45 is turned by means of the head 8.

With the above described arrangement of parts, the strip or plate constituting the 50 movable contact 6 is preferably mounted on the spindle so that it lies in or tends to return to the general plane of the fixed contacts 3, for which purpose a washer 16, of the same thickness as the contact-supporting structure 2 is placed on the spindle 5 between said contact strip and the top face of the supporting structure 1.

55 In assembling the parts of the device made as above described, the finger 13 of the movable contact 6 is placed upon the top face of any one of the fixed contacts 3, for example, as indicated in Fig. 3, that one at the extreme left hand end of the series. Under these conditions, the body of said 60 movable contact as well as its two fingers

are sprung upwardly out of their normal plane so that the second finger 12 projects at a higher level than the finger 13.

If now the handle 8 be moved in such a direction as to cause the contact 6 with its 70 fingers to move in the direction of the arrow (Fig. 3), the finger 13 slides downwardly on and in electrical contact with the top face of the fixed contact 3 which it engages, and as it so moves the level of the finger 12 75 is lowered so that its advancing edge engages and is moved down by the bevelled left hand edge of the same fixed contact as shown in Fig. 4. As a result, as the movement of the handle continues, the finger 12 80 passes onto and in full engagement with the under face of said contact; the first finger 13 lying immediately under the projecting portion 7 of another fixed contact but being held out of engagement therewith (Fig. 5) 85 because of its connection with the relatively stiff yet springy movable contact strip which however, is now sprung below its normal plane or position of repose.

The continued movement of the handle 90 still further springs the movable contact strip 6 below its normal plane until when its finger 12 finally passes off of the first fixed contact 3^a, it is instantaneously snapped or moved therefrom into engagement with 95 the under side of the second fixed contact 3^b (Fig. 7) which is cleared by or spaced away from the finger 13. The latter however by reason of the stiffness of the movable contact strip, cannot move into engagement with the under side of the third fixed contact 3^c, and as the handle 8 is further turned from left to right, the finger 12 successively snaps from engagement with the 100 underside of each fixed contact onto the 105 underside of that next adjacent it, in each case instantaneously breaking any current flow between it and said contact but without at any time simultaneously engaging two 110 adjacent fixed contacts. The second finger 13 remains spaced away from the fixed contacts during such movement and operation.

If now the direction of movement of the head or handle 8 be reversed so that it is turned in a counter clockwise direction, the 115 left hand edge of the finger 13 comes into engagement with and slides upwardly first on the bevelled edge or side of the nearest one of the fixed contacts 3 on its left side and then onto the flat top face thereof (Figs. 120 8 and 9), while the finger 12 similarly slides upwardly in engagement with the under face of the same fixed contact. After the finger 12 disengages this under face, it continues to rise above the plane of the fixed contacts as the finger 13 slides upwardly over the top face of the fixed contact 3^b for example (Fig. 10) until it finally snaps off of the highest portion of said fixed contact 125 and instantaneously thereafter comes into 130

engagement with the top face of the first fixed contact 3^a upon which it may be moved upwardly until further counterclockwise movement of the movable contact is prevented by its engagement with the stop 15.

Regardless therefore of the position of the movable contact 6, its finger 12 if moved in a clockwise direction, will successively but independently engage the under faces of the 10 fixed contacts to the right of it and if its direction of movement be reversed its finger 13 will slide into engagement with the top face of that fixed contact last engaged by the finger 12 and will thereafter successively 15 and independently engage the top faces of the fixed contacts to the left as its movement is continued. Obviously at no time is it possible for either or both of the fingers of the movable contact to simultaneously engage 20 two of the fixed contacts, and its construction is such that it necessarily moves from one of the latter into engagement with the other at a relatively high speed, dependent upon its own resiliency and the proportions 25 and dimensions of the various coacting parts. There is therefore practically no arcing between contacts owing to the quick breaks invariably made and there is no possibility of a movable contact making any 30 but a quick and good contact with each fixed contact which it engages.

It should be particularly noted that the portions 12 and 13 of the movable contacts are both of a greater width than the width 35 of the spaces between the fixed contacts, although by reason of the construction above described there is no possibility of the short circuiting of any two of said fixed contacts by the movable contact. The switch is therefore 40 particularly adapted for use in connection with that class of electrical apparatus wherein it is not permissible to even momentarily short circuit or permit connection of conductors leading to any adjacent pair of 45 contacts.

If desirable or found advisable I may without departing from my invention protect the fingers 12 and 13 of the movable contact 6 from possibility of short circuiting two 50 adjacent fixed contacts when moving between them from a position on one side of their plane to a position on the opposite side thereof. For this purpose I attach plates of insulating material 21 and 22 to said 55 fingers as shown in Fig. 17, holding them in the desired position by rivets 20 or other suitable means. Obviously these protecting plates or pieces of insulating material would be applied to those faces of the fingers 12 and 13 which were not intended to make 60 electrical engagement with the fixed contacts and in the case shown the insulating piece 22 could be applied to the upper face of the finger 13 and to the under face of the finger 12.

It is to be noted that my invention is not limited to a construction in which the fixed contacts or their engaging faces are arranged all in one plane or even in parallel planes, for, without departing from said 70 invention, I may mount the fixed contacts so that they lie in a cylindrical surface as shown in Fig. 18 and provide a movable contact having fingers which cooperate with said fixed contacts as hitherto described. In 75 Figs. 18 and 19 the fixed contacts 90 are shown as so-formed or mounted as to lie in a cylindrical surface. A movable contact arm 91 is pivotally mounted at 92 and has projecting from its free end a resilient piece 80 93 carrying a pair of contact fingers 94 and 95 which as said arm is swung on its pivot, cooperate with the fixed contacts 90 as described in connection with the other form 85 of my invention. With this construction of the movable contact, as with that shown in the foregoing figures, it will be noted that the operative faces of the contact fingers are so arranged and mounted as to lie parallel with the face of that fixed contact which 90 they engage at any given time,—a valuable feature of the invention insuring good contact and avoiding heating.

I claim:

1. The combination in an electric switch 95 of a series of fixed contacts mounted to lie substantially within a plane; with a movable contact having two portions formed and positioned to respectively engage opposite faces of the fixed contacts when it is moved 100 in opposite directions.

2. The combination in an electric switch of a series of fixed contacts mounted to lie substantially within a plane; with a movable contact having two portions formed and positioned to respectively engage opposite faces of the fixed contacts when it is moved 105 in opposite directions, said fixed contacts including portions cooperating with the movable contact to automatically shift its two 110 engaging portions from one side to the other of the plane of said fixed contacts.

3. The combination in an electric switch of a movable contact including two contact fingers; with a series of fixed contacts each having two faces for cooperation with the movable contact and each including a portion formed to cause one of said fingers to engage one of its faces when it is moved 115 in one direction and to engage its other face when it is moved in the opposite direction.

4. The combination in an electric switch of a series of fixed contacts mounted to lie substantially within a plane and each having two opposite faces inclined to said plane; with a movable contact formed to electrically engage either face of said fixed contacts and free to move between the latter when its direction of movement is reversed, 120 said fixed contacts and said movable contact 125 and 130.

- tact bearing such relation that the latter may snap from engagement with one fixed contact into engagement with another. 60
5. The combination in an electric switch 65 of a series of fixed contacts each having two opposite faces; with a movable contact formed to engage either face of said fixed contacts and free to move between two of the latter and maintain the circuit closed 10 when its direction of movement is reversed, said contacts being so related that said movable contact may instantly snap from one fixed contact to another. 15
6. The combination in an electric switch 20 of a series of fixed contacts of a movable contact including two contact fingers laterally displaceable by the fixed contacts and free to engage opposite faces thereof respectively when the direction of the movable contact is reversed. 25
7. The combination in an electric switch 30 of a supporting structure; a series of fixed contacts mounted thereon and each including a projecting portion having oppositely placed flat faces lying at an acute angle to the plane of the fixed contacts and each also having relatively sharp side edges; a movable contact having two resiliently supported contact fingers free to pass between the fixed contacts and formed to be automatically shifted from one side of the plane thereof to the other side of said plane when the direction of movement of the movable contact is reversed. 35
8. The combination in an electric switch 40 of a series of relatively fixed contacts; a movable contact having two fingers for engagement with the fixed contacts, said fingers and the fixed contacts being all inclined to the plane of movement of the movable contact and said fingers being free to pass from one side of the plane of the fixed contacts to the other side thereof when the direction of motion of the movable contact is reversed. 45
9. The combination in an electric switch 50 of a series of fixed contacts each having a projecting portion; with a movable contact having fingers formed to electrically engage the opposite faces of said projecting portions of the fixed contacts, and both free to pass from one side to the other of the plane of said contacts when their direction of movement is reversed. 55
10. The combination in an electric switch 60 of a series of fixed contacts each having double contact faces; a movable contact having two fingers formed to respectively engage opposite faces of said fixed contacts and both shiftable from one side to the other of the line of the fixed contacts when the direction of movement of the movable contact is reversed. 65
11. The combination in an electric switch 70 of a series of fixed contacts each having double contact faces lying in inclined parallel planes; with a movable contact having a pair of contact fingers formed to respectively cooperate with the two faces of said fixed contacts and shiftable from one side to the other of the line of said fixed contacts when the direction of movement of the movable contact is reversed; with insulation covering one side of each of said fingers. 75
12. The combination in an electric switch 80 of a series of fixed contacts each having double contact faces lying in inclined parallel planes; with a movable contact having a pair of contact fingers formed to respectively cooperate with the opposite faces of said fixed contacts and shiftable from one side to the other of the line of said fixed contacts when the direction of movement of the movable contact is reversed; with insulating material on one side of one of said fingers and on the opposite side of the other finger. 85
13. In an electric switch, the combination 90 with a series of fixed contacts each having a portion lying at an acute angle to the line of such series; of a movable contact having a pair of flat fingers twisted to lie substantially parallel with the inclined portions of said fixed contacts. 95
14. An electric switch comprising a series 100 of fixed contacts, each contact having a portion inclined at an acute angle to the line of such series; and a movable contact comprising a pair of fingers twisted to lie substantially parallel with the inclined portions of said fixed contacts, said fingers being spaced a distance substantially equal to the thickness of said inclined portions of said fixed contacts. 105
15. An electric switch comprising a series 110 of fixed contacts mounted to lie substantially within a plane; said fixed contacts having portions inclined at an acute angle to said plane; and a movable contact having a pair of fingers twisted to lie in planes substantially parallel with the planes of the inclined portions of the fixed contacts, said contact fingers being spaced vertically and horizontally. 115

ADOLPH W. SCHRAMM.
